UNITED STATES PATENT OFFICE.

WALDEMAR N. OLSON, OF CHICAGO, ILLINOIS, ASSIGNOR TO REYNOLDS ELECTRIC COMPANY, A CORPORATION OF ILLINOIS.

PERIODIC ROTARY SWITCH.

Application filed April 22, 1925. Serial No. 25,175.

This invention relates to that class of electric circuit controllers by means of which one or more circuits may be opened and closed or controlled for lighting and extinguishing an electric lamp or lamps, or for signalling or other purposes.

The principal object of my invention is to provide a compact, simple, economical and efficient electric circuit controlling mechanism adapted to be used for making and breaking an electric circuit or circuits for lighting and extinguishing a lamp or lamps, such, for example as the lamp or lamps of an electric sign or signalling device, or for operating electrically actuated devices, or for signalling or other purposes in an efficient manner.

A further object of the invention is to provide an electric circuit controller, or circuit making and breaking mechanism of the type having a rotary contact member or contact drum having one or more contacts adapted to be moved into and out of engagement with one or more stationary brushes or other similar or suitable contact members, for making and breaking an electric circuit or circuits, such, for example, as the electric circuit or circuits of an electric sign or sign flasher, or for signalling or other purposes, which will be compact, durable, comparatively noiseless, economical and efficient in operation.

Other and further objects of the invention will appear from the following description and claims, and from an inspection of the accompanying drawings, which are made a part of this specification.

The invention consists in the features, combinations, details of construction and arrangement of parts herein described and claimed.

In the accompanying drawings—

Figure 1 is a view in central vertical section of an electric circuit controller, or circuit making and breaking mechanism, constructed in accordance with my invention;

Fig. 2 is a view in transverse section, taken on line 2—2 of Fig. 1, looking in the direction indicated by the arrows;

Fig. 3 is an enlarged detail view in transverse section, taken on line 3—3 of Fig. 1, looking in the direction indicated by the arrows; and shows a shock-absorbing or cushioning spring operatively connected with the rotative contact member or drum, for reducing the shocks to which said drum and other parts are subjected in use;

Fig. 4 is a similar enlarged detail view in transverse section, taken on line 4—4 of Fig. 1, looking in the direction indicated by the arrows, and showing the spring mechanism operatively connected with the rotative contact member or drum and with the driving shaft, for rotating the drum or contact member with respect to the shaft, and for permitting the rotation of the shaft with respect to the drum and the slowing down and acceleration of the movement of the drum with respect to the shaft and with respect to the stationary contacts or brushes;

Fig. 5 is an enlarged detail view taken on line 5—5 of Fig. 1, looking in the direction indicated by the arrows, and showing the means for automatically releasing and stopping the rotative contact member or drum, the releasing cam and the stopping and releasing pawl or detent lever being shown in full lines in the position they would occupy when the pawl comes into contact with the stationary stop of which there may be one or more, said cam and pawl being shown in broken lines in releasing position;

Fig. 6 is a similar detail view of the parts shown in Fig. 5, showing the releasing cam and the stopping and releasing pawl or detent lever in releasing position in full lines, and in stopping position with the pawl in engagement with a lower stationary stop, in broken lines;

Fig. 7 is a similar view of the parts shown in Figs. 5 and 6, showing the releasing cam and pawl in releasing position in full lines as they would appear after the movement of said parts from the position in which they are shown in Fig. 6 to the position shown in said Fig. 7, the pawl being shown in broken lines as it would appear upon being snapped or moved forward with the

rotative drum into a position to cause the cam to engage the rear lever arm of the pawl so as to set or move the latter to position to engage the next stationary stop for stopping the drum;

Fig. 8 is a view in transverse section, similar to Fig. 2, showing a modified form of my improved circuit controller having three stationary stops, and three stationary 10 brushes or contacts each adapted to engage one or more contacts on the rotative drum which may have three or any desired number of contacts for engaging the brushes;

Fig. 9 is a detail view in horizontal section showing the selective stationary contact fingers or brushes in contact with the rotative contact member or drum, and showing the construction of the periphery or brush-engaging peripheral surface of the 20 drum, and an air-containing depression or pocket in the surface of the drum, at the circuit-breaking end of the contact segment, and

Fig. 10 is a detail view or development of 25 the periphery of the drum, showing the conductive element and peripheral air-pockets.

In constructing a circuit controller or circuit making and breaking mechanism in accordance with my invention, I provide a 30 frame or casing 1 which may be of any desired well known or suitable form adapted to support and enclose or shield the moving parts to be mounted therein, and by preference comprise a plurality of sections, such, 35 for example, as end sections 2 and 3 and a central section 4 which are rigidly secured together by suitable securing means. A base or bottom wall 5 may be secured to or formed integrally with the outer casing walls 40 6 of one or more of the connected casing sections or frame members. The outer casing walls may be circular or in part circular and in part angular, or of any suitable form; and transverse end walls 7 and 8 and intermediate 45 upright transverse walls or frame members 9 and 10 are so disposed and spaced apart that the casing is divided into compartments 11, 12, 13 and 14. The compartment or chamber 11 formed by the end section 2 is adapted to contain the contact drum or rotative contact member and brushes, and the stopping and releasing mechanism and drum-actuating mechanism which will be 50 more fully described. The compartment or chamber 12 encloses the motor. The compartment 13 serves as a gear chamber or compartment. And the compartment or chamber 14 is adapted to contain the motor leads and connections and other electric conductors which may be of any desired ordinary and well known or suitable form.

An upright inner transverse supporting frame member or plate 15, of suitable insulating material, such for example as insulating fiber, is rigidly secured to a suitable

support which may consist of the inner transverse wall 9 having a series of bosses 16 which project from said wall. This supporting and insulating plate or member 15 is secured to the ends of said bosses 16 by means of threaded screws 17 inserted through perforations in the plate and in threaded engagement with suitably threaded perforations or openings in the bosses 16 or wall 9. The plate 15 is thus supported in the compartment 11 in spaced apart relation to the transverse inner wall 9, and is provided with a central opening through which the rotative contact member or drum and drum-actuating shaft herein-after described, may extend.

A bracket or supporting member 18 which may have one or more arms, is provided and adapted to be rigidly secured to the inner transverse upright wall 9 or the bosses 16, which are, by preference cast in one integral piece with said wall 9. This bracket may be removably secured in position by means of the securing screws 17, or other suitable securing means, and is provided at its outer or upper projecting end with an opening or journal bearing 19 which is, by preference, located in position to extend into or through an opening 20 in the upright end wall 7 of the casing or frame. This end wall 7 is a 95 part of the casing section 2, and is detachably secured to the central casing or frame member 4 by suitable securing means, such, for example, as one or more screws 21 inserted through the end wall 7 and anchored in the bracket 8 which is in turn connected with and supported by the inner wall 9.

A drum actuating or driving shaft 22 is journaled in suitable supporting journal bearings one of which may be the bearing or opening 19 in the supporting arm or bracket 18, and the other of which may be an opening or bearing 23 in the inner transverse upright frame member or wall 9 through which said shaft extends. The driving shaft 22 is operatively connected with a suitable source of power which may be of any desired well known or suitable form, such for example, as an electric motor 24 located in the compartment 12 and having a core or rotor 25 fixed to a rotative motor shaft 26 journaled in suitable bearings 27 and 28 in the casing or frame. The motor may be of any suitable form.

The shaft 22 is operatively connected with 120 the motor 24, which may be either an alternating current motor or a direct current motor, by suitable connecting means, such, for example, as a train of gears comprising a motor pinion or gear wheel 30 fixed to the motor shaft 26, a spur gear wheel 40 fixed to the rotative drum-actuating or driving shaft 22, and connecting gears which may comprise, connected gear wheels 31, 33, 34, 36, 37, and 39, which form a connection be- 130

tween said gears 30 and 40. The gears 31, 34 and 37 are supported on stub shafts 32, 35, and 38 respectively.

A rotative contact element or snap contact

- 5 drum member 41 which is, by preference, cylindrical and comprises a continuous metallic contact member or annular contact 42 and one or more interrupted segmental metallic contact elements or members 43
- 10 mounted upon or fixed to an annular or cylindrical insulating body or drum member 44 of insulating material, such for example, as molded commercial fiber, hard rubber, or laminated fibrous or insulating
- 15 material or composition of any ordinary and well known or suitable form, is provided and rotatively mounted upon a suitable support. The rotative contact element or drum 41 is, by preference, loosely mounted on a driving shaft, such, for example, as the driving shaft 22 which extends loosely through a suitable axial opening in the drum or rotative contact member 41, so that the drum may be operatively connected with and in relatively
- 20 25 movable relation to the shaft. The rotative contact member or drum 41 is, by preference, provided with an inner or axial hollow bearing or sleeve member 44' which loosely encircles the driving shaft 22 and
- 30 35 forms a hub or annular end bearing portion on which is mounted an end collar or plate 45, which is detachably secured in fixed relation to the drum body 44 and sleeve 44' by suitable securing screws or other ordinary or suitable securing means. The end plate or collar 45 has a segmental slot or opening 46 which is made by cutting away a segment of the periphery of the collar or plate; and the main body or molded insulating body
- 40 45 portion 44 of the rotative contact element or drum 41 is provided with a segmental slot or opening 47 and with a suitable space 48, for admitting the spring mechanism and connecting pins or bosses by means of which the drum is operatively connected with or in flexible yielding relation to the shaft 22.
- 50 55 A drum-actuating or spring-tensioning crank arm or member 49 is fixed to the driving shaft 22 by means of a securing pin 50, or other suitable securing means. And a spring-tensioning or drum-actuating crank pin or boss 51 is fixed to the crank arm or lever 49 and extends into the segmental openings 46, 47 in parallel relation to the axis of the shaft 22 which is concentric with the drum or rotative contact element 41. A spring-engaging pin or boss 52 is anchored in and in fixed relation to the central or main insulating body portion 44 of the rotative contact element or drum 41. And one or more drum-actuating springs 53, 53, 53, encircle the shaft 22, one end of each spring 53 being secured to the crank pin or boss 51, and thereby connected with the crank arm 49 and shaft 22, and the other end of each

of said springs 53 being connected with the pin or boss 52 on the drum, and thereby attached to the drum or rotative contact member 41.

The drum-actuating resilient means or 70 spring mechanism thus provided, for operatively connecting the rotative contact element or drum 41 with the driving shaft 22, comprises, by preference, a series of spiral springs located side by side on the inside of 75 the rotative contact member or drum 41 and encircling the sleeve 44 and shaft 22, said springs being adapted to be stretched to a suitable tension or tensioned by the rotation of the shaft 22 with respect to the rotative 80 contact element or drum 41, and being adapted to actuate or rotate the drum or rotative contact member 41 so as to cause the same to have a quick snappy rotative move- 85 ment which is faster than the rotative move- ment of the shaft 22, when the rotative contact member or drum is released and permitted to be actuated by the action or ten- sion of said spring mechanism or springs 53.

The drum-actuating spring mechanism, 90 comprising the one or more spiral springs 53—by preference a plurality of said springs arranged side by side and encircling the shaft 22 and located inside the drum or rotative contact element 41—is adapted to 95 be wound to a suitable tension by the rotation of the driving shaft 22 in the same direction in which the rotative tension member or drum 41 is rotated or actuated by the action or tension of said spring mecha- 100 nism or resilient drum-actuating means. In other words, the tension of the drum-actuating resilient means or spring mechanism, comprising the spring or springs 53, tends to rotate the drum or rotative snap circuit- 105 controlling contact member 41 in the same direction the shaft 22 is rotated. And a resilient shock-absorbing element or spring 54, which is by preference in the form of a spiral spring wound in an opposite direc- 110 tion to that in which the springs 53 are wound, encircles the shaft 22 and sleeve 44' inside the drum 41 and beside the series of springs 53, one end of said shock-absorb- 115 ing spring or reaction spring 54 being secured to the pin or boss 52 on the drum, and the other end of said spring 54 having an elongated loop portion 55 into which the crank pin or boss 51, which is connected and moves with the crank arm 49 and shaft 22, 120 extends, one end of said loop portion of the spring 54 being adapted to engage a shoulder 56 formed at the end of the elongated segmental slot 47 by the end plate 49 or the drum 41, of which said end plate 45 may be said to form a part. The tension of the spring 54, which serves as a cushion- 125 ing or shock-absorbing spring, is in an oppo- site direction to that of the springs 53. In other words, the tension of the spring 54 130

tends to rotate the drum 41 in an opposite direction to that in which it is rotated by the springs 53. And the shock-absorbing or cushioning spring 54 is thus adapted to 5 yieldingly resist the movement of the drum 41 as it is rotated by the springs 53. Washers 72 are interposed between the spiral or volute springs 53 and 54, for separating them.

10 As the tension of the shock-absorbing reaction spring or cushioning spring 54 counteracts and tends to resist the action or tension of the drum-actuating springs 53, it will be readily understood that the drum 15 41 is so operatively connected with the shaft 22 by the resilient connecting means comprising said springs 53 and 54, that the drum may be rotated by the rotation of the shaft 22 which is thus operatively connected 20 with the drum, and that the drum is also adapted to be rotated with respect to the shaft, or at a speed which may vary with respect to the speed of rotation of the shaft, by the action of the resilient drum-actuating 25 means or springs 53. The shaft may therefore be rotated at a uniform speed or at any desired predetermined speed; and the rotative movement of the drum may be accelerated and diminished, or increased 30 and decreased with respect to the speed of rotation of the shaft. And there may be certain periods in the operation of the device, in which the drum will rotate at the same speed and in the same direction with 35 the driving shaft 22. During other periods the drum may be stopped while the shaft 22 continues to rotate. And during another period or periods, the drum, upon being released, will be moved or snapped forward 40 by the action of the springs 53 at an accelerated or more rapid speed of rotation than that of the shaft, so as to enable a quick snappy movement of the drum 41 to be obtained which will tend to cause a correspondingly quick make and quick snappy 45 break of the electric circuit which is to be controlled by the action or movements of the circuit-controlling mechanism constructed and adapted to operate in accordance 50 with my invention.

Stopping and releasing means for automatically stopping and releasing the rotative contact member or drum 41, is provided, as follows:

55 One or more stops 57, which are, by preference stationary and arranged at suitable uniform distances from each other and at equal distances from the axis of the drum 41 and shaft 22, are mounted in a stationary support, such, for example, as the stationary frame member 9. These stops are located 60 adjacent to the end of the rotative contact member or drum 41, and may be in the form of stop pins or shoulders, or teeth adapted to be engaged by one or more pawls 65

or movable detents or stop levers 58 pivotally mounted on the drum or rotative contact element 41 by means of a pivot pin 59 for each pawl or stop lever 58.

In the form of circuit controller shown 70 in the accompanying drawings, only one pivoted pawl or stop lever 58 is shown or required. But there may be two or more of the stationary stops 57, by preference, one for each brush or electrically conductive 75 contact finger 60 to be engaged by the rotative contact element or drum contact member 43 successively, selectively, or in predetermined order. In the form of the device shown in Figs. 1 to 7 inclusive, two 80 stationary stops 57, and two selective brushes or contact fingers 60 are shown; while, in the form of the device shown in Fig. 8, three stationary stops 57, and three 85 selective contact fingers or brushes 60, are shown. Any desired number of stationary stops 57 and brushes or spring-pressed stationary brushes or contact fingers 60 may be employed.

The movable pawl or stop lever 58, which is pivotally mounted on an end face of the body of the drum 41 by means of a pivot pin 59 anchored in the insulated body portion 44 of the drum, is, by preference angular, or in the form of a bell crank lever having a forward lever arm 61, the forward angular end 62 of which is adapted to be moved inward and outward with respect to the axis of the drum or rotative contact member 41, or inward into position to engage, and outward into position to release or pass around the stationary stops 57 successively or in predetermined order.

The movable pivoted pawl or stop lever 58 also has a rear angular lever arm or tail piece 63 which extends rearward from the axis of the pawl substantially at right angles to the forward lever arm 61 and in fixed relation to the same, so as to form an angular space or recess 64 on the inner side or margin of the pawl. A pawl-actuating or stopping and releasing member or cam 65 is fixed to the shaft 22 and extends into the angular space or recess 64 on the inner side of the pivoted pawl or stop lever 58, in position to engage and actuate said pivoted pawl or stop lever.

This pawl actuating member 65 may be in the form of a cam or projecting shoulder or finger or pawl-engaging member of any suitable form adapted to engage and operate the pawl or stop lever 58 in one direction, to cause the pawl to engage a stop 57, or in an opposite direction, to cause the pawl to disengage or release or pass around or beyond an adjacent stop 57 as required.

And I prefer to mount the pawl or pivoted stop lever 58 on the drum or rotative contact element 41 and the stops 57 on a stationary support adjacent to and in the path

- of movement of the pawl, rather than to reverse the relative positions of said pawl and stationary stops by placing the pivoted pawl on a stationary support in position to be engaged and operated by the cam, or in position to be moved into and out of engagement with stops mounted on the rotative drum or contact member 41 instead of on a stationary support.
- 10 And although I have here shown only one selective segmental electrically conductive contact member or segment 43, any desired number of these selective segmental contact members or elements may be employed. And the continuous annular contact band 42 may be either on a separate drum or support on and movable with the shaft 22, or on the same drum 41 with the segmental contact elements or segments 43. I prefer, however, to make the continuous annular contact member or band 42 and the selective segmental contact element or segment or segments 43 in one integral piece of metal, which is mounted on a drum or body of insulating material 44, the continuous or endless annular contact band 42 being adapted to continuously engage a stationary feed brush or current supply conductor 66, which is by preference mounted on one side of an upright stationary supporting plate 15 of insulating material, and the interrupted or segmental contact member or segment 43, being located, by preference, in position to extend on the opposite side of or through the supporting plate 15 into position to engage the brush or brushes 60 in successive or predetermined order so as to make or close a desired circuit or circuits, and in position to disengage such brush or brushes 60, to break or open a desired circuit or circuits, as desired or required, for making a signal or for any purpose.
- The feed brush 66 may be of any desired ordinary and well known or suitable form, such, for example, as a bar of carbon or metal or any suitable electrically conductive material, and is electrically connected with a source of electric current supply, said feed brush 66 being mounted in a suitable brush holder 67 which is provided with a spring 68 in engagement with and adapted to constantly tend to press and yieldingly hold the brush or contact finger 66 in yielding contact with the periphery of the rotative contact member 42 on the drum 41.
- The brushes or contact fingers 60 may be of identical construction with the feed brush 66, and are each mounted in a brush holder 69 having a spring 70 in engagement with and adapted to yieldingly hold and tend to press or feed said brushes 60 into yielding contact with the periphery of the segmental metallic contact member 43 and the periphery of the drum 41. The brush-holders 69 may be of identical construction with the brush-holder 67, or may be of any well known or suitable form, but are, by preference mounted on the opposite side of the insulation plate or frame member 15 which also supports the brush-holder 67 and brush 66, said insulation plate 15 being provided with a large opening 71 therein through which the drum or rotative contact member 41 extends. (See Figs. 1, 2 and 9.)
- The rotative contact member or drum 41 is, by preference, provided with a main body portion 44 formed of molded insulating material having the metallic or electrically conductive elements or parts 42, 43 embedded in and flush with the outer brush-engaging surface of the insulating material or body portion 44. In the form here shown the brush-engaging or contact surface of the drum or contact member 41 is the outer peripheral surface, and comprises the peripheral surfaces of the metallic contact elements or parts 42, 43 and the peripheral surface 73 of the molded or molded and machined insulating body member 44 which may be united and secured together in any well known or suitable manner.
- I provide at the circuit-breaking end of margin 74 and also, by preference, at the circuit-making end or margin 75 of each electrically conductive selective contact member or segment 43, an air-containing depression or pocket 76, 76, which is, by preference open and formed in the outer or peripheral face 73 of the molded or insulating body portion 44 of the drum or rotative contact member 41. (See Figs. 2, 4 and 9.)
- Each peripheral recess, cavity, depression or air pocket 76 is formed, by preference, in the peripheral face of the insulating body portion 44 of the drum 41, and extends transversely across the path of the brush or brushes 60 on the peripheral face of the drum, so as to provide an opening or hollow space between the corresponding or adjacent end margin or edge of the electrically conductive segment or contact element 43 and the margin or rim 77, or wall of such recess, cavity, depression or air-containing pocket 76.
- The recess or cavity 76 thus forms an open air pocket in the insulating body portion 44 of the drum and adjacent to the end margin or edge of the electrically conductive segment or contact member 43, which is of sufficient dimensions in length, width and depth to contain a quantity of air which tends to expand when heated and to disperse or spread and blow out or cool and extinguish the spark or arc, and minimize or prevent the burning or carbonization and breaking down or deterioration of the molded or insulating material of which the insulating body portion 44 of the drum is formed.
- The feed brush 66 is connected with the motor, and with a suitable source of electric

supply, and the brushes or contact fingers 60 are electrically connected with a source of electric supply and with electric lamps, signals, or other devices to be electrically actuated or connected with said brushes, in any desired ordinary and well known manner, and by any well known or suitable connecting means.

For example, the feed brush 66 is electrically connected with a motor by means of an electric conductor or wire 78. An electric wire 79 connects the brush 66 with a line wire or source of electric supply 80. An electric wire 81 connects one of the brushes 60 with an electric circuit 82 containing one or more electric lamps, signals or other electric devices 83, electrically connected with said wire 81 and with a line wire or other suitable conductor 84 by any desired ordinary and well known or suitable connecting means. An electric wire 85 connects a brush or contact finger 60 with an electric circuit 86 containing one or more electric lamps 87, or other electric devices which may be of any well known or suitable form, and are adapted to be electrically connected by suitable connecting means of any ordinary or suitable means with the line wire 84 or other electric conductor which may be of any ordinary or suitable form, according to the uses and purposes to be accomplished. (See Figs. 1 and 2.)

In Fig. 2, the contact segment 43 on the drum 41 is shown in position to form an electrical connection between the feed brush 66 and one of the brushes 60 which is connected with the circuit 86 by the wire 85, the circuit 86 containing lamps 87 being thus closed, and the circuit 82 which is connected with the other brush 60 by the conductor wire 81, being disconnected from the feed brush 66, and therefore open.

In Fig. 8 three selective brushes or contact fingers 60 instead of two, are shown. And the mechanism or device shown in said Fig. 8 corresponds in all other substantial respects with the mechanism or device shown in the other figures of the drawings and herein elsewhere described.

The operation of the automatically actuated stopping and releasing means will be readily understood by those skilled in the art, from the foregoing description, and from an inspection of the accompanying drawings, particularly Figs. 1, 3, 4, 5, 6, 7, and 9.

In Fig. 5 the pawl 58 is shown in full lines in the position which it would occupy upon coming into contact with the upper stationary stop 57. It will be readily understood that the parts shown in Figs. 5, 6 and 7, are intended and adapted to rotate in a counter-clockwise direction, as indicated by the arrows. The rotation of the shaft 22 with its cam 65 from the position shown in

full lines in Fig. 5 to the position shown in broken lines in said figure, will release the pawl 58 from its engagement with the stop 57, as indicated in said figure. Upon being thus released the drum 41 with the pawl 58 will be snapped or rotated forward at a speed exceeding the speed of rotation of the shaft and cam, by the action of the volute springs 53, first to the position shown in full lines in Fig. 6, and onward to the position shown in broken lines in Fig. 6, and in full lines in Fig. 7, so as to cause the pawl to engage the other or lower stop 57, as shown in Fig. 6, to be again released and rotated in the direction indicated by the arrows to the position indicated in broken lines in Fig. 7.

The cam 65 rotates with the pawl 58 and drum 41, but at the same speed of rotation with the shaft 22 to which the cam is fixed. And the drum 41 or rotative contact member, is actuated by the spiral or volute springs 53, which are resisted by the spring 54, whenever the drum is released by the automatic stopping and releasing means comprising the cam 65, pawl 58 and stop or stops 57, of which there may be one or any desired number.

The drum or rotative contact element 41 is thus rotated with a quick snappy movement at a speed in excess of the speed of rotation of the shaft 22 and its cam 65, and in the same direction of rotation, during the making and breaking of the circuit. The movement of the drum with respect to the shaft and releasing cam is retarded by the action of the shock-absorbing spring 54 before being brought to a stop, which is thus accomplished without any unnecessary shocks. And the entire device is compact, simple and economical in construction and operation, and durable, and not liable to get out of order or to be accidentally stopped or hindered in its efficient and continuous and uninterrupted operation.

I claim:

1. In a device of the class described, the combination of a driving member, a driven member, resilient connecting means connected with and adapted to effect an operative connection between said driving and driven members, a stationary stop mounted on a suitable support, a movable stopping and releasing member on and movable with said driven member and adapted to operatively engage said stationary stop, and means connected with and adapted to be operated by said driving member for automatically moving said movable stopping and releasing member into and out of position to operatively engage said stationary stop.

2. In a device of the class described, the combination of a driving member, a driven member, resilient means adapted to effect an operative connection between said driving and driven members, a plurality of sta-

- tionary stops, a movable stopping and releasing dog or pawl on and movable with said driven member and adapted to be moved into and out of engagement with said stationary stops successively, and pawl-actuating means connected with and adapted to be operated by said driving member and acting to automatically move said movable pawl into and out of position to engage said stationary stops respectively.
3. In a device of the class described, the combination of a driving member, a driven contact member, resilient means adapted to effect an operative connection between said driving member and said driven contact member, a stationary stop, a movable stopping and releasing member on and movable with said driven contact member, and means on and movable with said driving member for automatically moving said stopping and releasing member on said driven contact member into and out of operative engagement with said stationary stop.
4. In a device of the class described, the combination of a rotative driving member, a rotative driven contact member, resilient connecting means adapted to effect an operative connection between said driving and driven members, a stationary stop mounted on a suitable support, a movable stopping and releasing pawl mounted on and movable with said driven contact member, and a pawl-engaging member on and movable with said rotative driving member and acting to automatically move said pawl into and out of operative engagement with said stationary stop.
5. In a device of the class described, the combination of a rotative driving member, a rotative driven contact member, resilient connecting means adapted to effect an operative connection between said driving and driven members, a stationary stop mounted on a suitable support, a movable stopping and releasing member mounted on and movable with said driven contact member, and an arm member on said rotative driving member and adapted to automatically engage and move said movable stopping and releasing member alternately into and out of operative engagement with said stationary stop.
6. In a device of the class described, the combination of a rotative driving member, a rotative driven contact member, resilient connecting means adapted to effect an operative connection between said driving and driven members, a stationary stop, a movable stopping and releasing pawl pivotally mounted on said rotative driven member, and a cam on said rotative driving member and adapted to operatively engage and automatically move said pivoted pawl in one direction on its axis into position to engage said stationary stop and in an opposite direction into position to release said stationary stop.
7. In a device of the class described, the combination of a rotative driving member, a rotative driven contact member, resilient connecting means adapted to effect an operative connection between said driving and driven members, a stationary stop, a movable stopping and releasing lever member pivotally mounted on said driven member and having a plurality of arm portions provided with a space therebetween, and an arm on said rotative driving member and extending between said projecting arm portions of said pivoted stopping and releasing member and adapted to automatically move the latter on its pivot into and out of position to operatively engage said stationary stop.
8. In a device of the class described, the combination of a rotative driving member, a rotative driven contact member, resilient connecting means adapted to effect an operative connection between said driving and driven members, stopping and releasing means comprising a stationary stop mounted on a suitable support, a movable stopping and releasing pawl mounted on and rotative with said driven contact member and having a plurality of lever arms provided with a space therebetween, and a cam on said rotative driving member and extending between and in position to operatively engage said lever arms alternately, to move said pawl into stop-engaging and releasing positions alternately.
9. In a device of the class described, the combination of a rotative driving member, a rotative driven contact member having electrically conductive peripheral contact portions suitably insulated, stationary electrically conductive contact members or brushes adapted to operatively engage said electrically conductive contact portions of the driven contact member, resilient connecting means adapted to effect an operative connection between said driving and driven members and acting to permit the driven contact member to rotate at a speed which varies with respect to the speed of rotation of the driving member, stationary stopping means comprising one or more stationary stops, a movable stopping and releasing member mounted on and movable with said rotative driven contact member, and an actuating and releasing member or cam on and rotative with said rotative driving member and adapted to engage and automatically move said movable stopping and releasing member located on the driven contact member into and out of operative engagement with said stationary stop.
10. In an electric circuit controller of the class described, the combination of a rota-

- 5 tive driving member, a rotative driven contact member having suitably insulated electrically conductive contact portions, stationary electrically conductive brush members adapted to operatively engage said electrically conductive contact portions of the driven contact member, resilient means connected with and forming an operative connection between said rotative driving 10 member and said driven contact member and adapted to permit the driven contact member to rotate at a speed which varies with respect to the speed of rotation of the rotative driving member, stationary stopping means comprising a plurality of stops mounted on a suitable stationary support, a movable stopping and releasing pawl member pivotally mounted on the rotative driven contact member, and a rotative cam member on said rotative driving member and adapted to engage and automatically move said pawl member into and out of position to operatively engage and release said stationary stopping means.
- 15 11. In a device of the class described, the combination of a rotative driving member, a rotative driven member comprising an electrically conductive contact element and having a body portion formed of insulating material, resilient means comprising a spring encircling said rotative driving member, said spring having its opposite extremities operatively connected with said driving and driven members respectively, 20 retarding and releasing means comprising a stationary stop mounted on a suitable support, a pawl pivotally mounted on said driven member, and a pawl-operating member fixed to said driving member and adapted to engage and automatically operate said pawl in opposite directions on its axis alternately, to cause the pawl to alternately engage and release the stationary stop.
- 25 12. In an electric circuit controller, the combination of a rotative driving shaft, a rotative driven hollow drum member comprising an electrically conductive contact element and a drum body portion formed of insulating material, a crank arm fixed to said shaft, resilient means comprising a spiral spring located inside the hollow drum and having its opposite ends connected with said drum and said crank arm respectively, said spring tending to rotate the drum in the same direction in which the shaft is adapted to rotate, shock-absorbing means tending to yieldingly resist the rotation of the drum in the direction in which it is actuated by said spring, and means for temporarily retarding then releasing said rotative drum.
- 30 13. In an electric circuit controller, the combination of a rotative driving shaft, a rotative driven hollow drum member comprising an electrically conductive contact element and a drum body portion formed of insulating material, a hub on said rotative driven member and encircling the driving member, resilient means comprising a spring encircling said hub and connected at its opposite extremities with said driving and driven members respectively, said spring tending to rotate the said driven member in the same direction in which the driving member is rotated, stopping and releasing means comprising a stationary stop, a pawl pivotally mounted on said rotative driven member, and a pawl-operating member fixed to said driving member and adapted to engage and automatically operate said pawl in one direction on its axis into position to engage said stationary stop and in an opposite direction to release the pawl from engagement with the stop.
- 35 14. In an electric circuit controller, the combination of a rotative driving shaft, a rotative driven hollow drum member comprising an electrically conductive contact element and having a drum body portion formed of insulating material, resilient means comprising a plurality of volute springs located inside of the hollow drum and each having its opposite ends connected with said drum and said driving shaft respectively, said springs tending to rotate the drum in the same direction in which the driving shaft is adapted to rotate, a reaction spring located inside the drum and having its opposite extremities operatively connected with and effecting a connection between said driving shaft and said drum respectively and acting to resist the rotation of the drum in the direction in which it is actuated by said first-mentioned springs, and means for temporarily retarding then releasing said rotative drum.
- 40 15. In a device of the class described, the combination of a rotative driving member, a rotative driven member comprising an electrically conductive contact element and a body portion formed of insulating material, a hub on said rotative driven member and encircling the driving member, resilient means comprising a spring encircling said hub and connected at its opposite extremities with said driving and driven members respectively, said spring tending to rotate the said driven member in the same direction in which the driving member is rotated, stopping and releasing means comprising a stationary stop, a pawl pivotally mounted on said rotative driven member, and a pawl-operating member fixed to said driving member and adapted to engage and automatically operate said pawl in one direction on its axis into position to engage said stationary stop and in an opposite direction to release the pawl from engagement with the stop.
- 45 16. In a device of the class described, the combination of a rotative driving shaft, a rotative hollow drum member comprising an electrically conductive contact element

and a drum-body portion formed of insulating material, resilient means comprising a spring located inside of said hollow drum and encircling said driving shaft, said spring having its opposite extremities connected with said driving shaft and said drum respectively, stopping and releasing means comprising a stationary stop mounted adjacent to the drum, a pawl pivotally mounted on said drum, and a pawl-operating member fixed to said driving shaft and adapted to engage and automatically operate said pawl in one direction on its axis into position to engage said stationary stop and in an opposite direction into position to release said stationary stop. 15

Signed at Chicago, in the county of Cook and State of Illinois this 9th day of April, 1925.

WALDEMAR N. OLSON.
